LUGGAGE CASE

Melvin H. Best, Pasadena, and Clair A. Samhammer,
Altadena, Calif., assignors to Shwayder Brothers, Inc.,
Denver, Colo., a corporation of Colorado

Filed May 31, 1962, Ser. No. 70,349

Term of patent 14 years

(Cl. D87—5)

FIG. 2.

FIG. 3.

FIG. 4.

FIG. 1 is a three quarter front perspective view of a luggage case embodying our new design;

FIG. 2 is a top plan view of the luggage case;

FIG. 3 is an end elevation of the luggage case; and

FIG. 4 is an enlarged, fragmentary elevation of the upper central portion of one end of the luggage case.

The essential features of our design reside in the portions shown in full lines.

We claim:

The ornamental design for a luggage case, as shown and described.
